UNITED STATES PATENT OFFICE.

THEODORE SPINNER AND OTTO WM. BOHLEN, OF ST. LOUIS, MISSOURI.

LAPPING MACHINE.

Application filed November 30, 1921. Serial No. 518,971.

To all whom it may concern:

Be it known that we, THEODORE SPINNER and OTTO WM. BOHLEN, citizens of the United States, residing at St. Louis, Missouri, have invented new and useful Improvements in Lapping Machines, of which the following is a specification, reference being had to the accompanying drawings.

Our invention relates to improvements in lapping machines and is particularly designed for use in connection with the reconditioning of cylinders for internal combustion engines.

Our object is to provide a machine of simple, durable and inexpensive construction comprising a support for an engine block, which is adjustable for adaptation to blocks of varying dimensions and means comprising a movable lapping element having adjustable devices for adapting it to cylinders of varying lengths and different relative spacings of cylinders.

Our improvements consist in the novel construction, arrangement and combination of elements, as hereinafter fully, clearly and concisely described, definitely pointed out in our claims and illustrated by the accompanying drawings, (2 sheets) in which:—

Figure 1 is an elevation of a machine constructed in accordance with our invention.

Figure 2 is an end view of the machine.

Figure 3 is a fragmental plan view of the machine, and

Figure 4 is an enlarged elevation of the movement for the lapping elements.

Referring to the drawings, 5 designates a frame comprising flanged rails 6 and 7 extending lengthwise of the frame and having bolt and slot connections 8 therewith whereby the two rails may be relatively laterally adjusted to fit therebetween an engine block, such as 9, and which rails are provided with spaced slots 10 for the securing of the engine blocks to the rails.

At the top of the frame there are bearings 11 in which is journalled a shaft 12 disposed lengthwise of the machine over the recited rails 6 and 7.

Carried by the shaft is a belt pulley 13 arranged for connection and disconnection with a source of power by a clutch 13^a.

By preference, at least a portion of the length of the shaft 12 is of non-circular section and mounted upon this portion of the shaft are one or more eccentrics 14, with

straps 15 for the support and operation of the lapping element or elements 16.

By preference we employ as the lapping elements, ordinary pistons which when reciprocated in the cylinders in the presence of an abradant, such as powdered emery and oil, act upon the cylinder surfaces to true and reshape them as well as clean them of carbon and other foreign matter.

For the varying the stroke of the lapping element, the eccentric 14 is provided with an opening 17 in eccentric arrangement in which there is mounted a second eccentric 18, having a non-circular opening 19 for fitment over the shaft 12 and which opening 19 is in eccentric arrangement relative to the second eccentric 18.

Obviously by rotating the second or inner eccentric 18 relative to the first or outer eccentric the path or orbit of the eccentric strap 15 will be varied to cause variation in the strokes of the lapping machine.

The opening 17 is provided with teeth 20 for mesh with a pinion 21 mounted in a cavity 22 formed in the second or inner eccentric, open to the opening 17 in the first or outer eccentric, and is held in place by straps 23, secured to the inner eccentric and which pinion includes a socket 21^a to provide for its rotation.

Obviously upon a rotation of the pinion 21, the inner eccentric may be readily rotated relative to the outer eccentric and when "set" may be locked in its selected set position as by a wedge 24.

For adapting the machine to varying cylinder lengths, we provide a threaded stem 25 extending from the eccentric strap which carries a bar 26 and connect with the bar a pair of threaded stems 27, 27 for connection with the box or bearing element 28 of the piston rod, which is the showing for the recited lapping element and which is, or may be, an ordinary piston.

What we claim as new is:—

1. A lapping machine for cylinder blocks of varying sizes comprising a frame for supporting the cylinder blocks, said frame having two cylinder blocks supporting beams and means for securing said beams in varying relation to accommodate the cylinder blocks of varying sizes, a lapping element, and means for actuating said lapping element.

2. A lapping machine comprising a frame having two cylinder block supporting beams

and means for securing said beams in varying spaced relation in order to accommodate cylinder blocks of varying sizes, a shaft supported by said frame in position above said beams, a lapping element, and means actuated by said shaft for actuating said lapping element, said means being adjustable for use with varying sized cylinders.

3. A lapping machine for cylinder blocks of varying sizes comprising a frame for supporting the cylinder blocks, said frame having two spaced supporting beams and means for adjusting said beams laterally of the frame to vary the distance between the beams to accommodate cylinder blocks of varying sizes, means associated with said beams for securing the cylinder blocks thereon, a rotary shaft, means for supporting said shaft on said frame above said beams, a lapping element, and means mounted on said shaft for actuating said lapping element.

4. A lapping machine for cylinder blocks of varying sizes comprising a horizontal frame for supporting the cylinder blocks,

said frame having two cylinder supporting beams spaced from each other laterally of the frame and means for securing said beams in varying spaced relation to support cylinder blocks of varying sizes, means associated with said beams for securing the cylinder blocks thereon, a rotary shaft, means for supporting said shaft on said frame above said beams, a lapping element, means mounted on said shaft for actuating said lapping element, and means for adjusting said actuating means for adapting said lapping element to cylinders of different lengths.

5. The machine as defined by claim 4 in which said last mentioned adjusting means comprises inner and outer eccentrics connected together whereby the former actuates the latter and means for varying the distance between the centers of said eccentrics.

In testimony whereof we hereunto affix our signature.

THEODORE SPINNER.
OTTO WM. BOHLEN.
